WHEELED JACK

George Quayle, Philadelphia, Pa., assignor to The
Yale & Towne Manufacturing Company, Stamford,
Conn., a corporation of Connecticut

Application October 25, 1938, Serial No. 236,866

24 Claims. (Cl. 280—46)

This invention relates to a type of lifting apparatus known in the art as a wheeled jack or dolly. I shall herein call it a wheeled jack.

A wheeled jack is a two-wheeled lifting device especially adapted for lifting one end of a semi-live skid platform, that is, a skid platform having two wheels at one end and two legs at its other end. By lifting that end of the skid platform which rests on legs, off said legs, and on to the wheels of the wheeled jack, the semi-live skid platform is converted into a full live skid platform, or the equivalent of a four wheel truck.

In my invention, I utilize a form of engaging means between the jack and the skid platform which is well known in the art, that is, a trunnion on the jack having a socket cooperable with a pin depending downwardly from the skid platform. My invention is equally useful should it be desired to use a pin on the trunnion and a socket on the skid platform, as is disclosed in some prior art constructions.

While I have indicated that the general type of structure disclosed by me is old in the art, I should like to point out generally several important advantages which are inherent in the structure which I have conceived and shall hereinafter disclose. Other advantages will appear as a study is made of the specification which follows. As a feature of my invention, I utilize a construction in which it is necessary that the operator assume the full weight of the load on the wheeled jack as by lifting it somewhat beyond its elevated position, before he can lower the skid platform on to its legs. Moreover, the release of the load is accomplished, preferably, solely through the operation of a lifting handle, rather than through additional means working in conjunction with the lifting handle. In this way, I prevent accidental release of the lifting mechanism and the free swinging of the handle through the application of the load to the wheeled jack. Those familiar with this art will fully appreciate the value of this construction, eliminating as it does the "flying handle" hazard.

As a further feature of my invention, I utilize a lifting handle or lever which is spring balanced at all times so as to remain in a vertical position without any effort on the part of the operator. This is an extremely desirable construction, and has long been sought for in the art. Moreover, the means whereby the balanced handle is obtained are simple, and the spring which is required to be used is enclosed so as to present a very slight appearance, and so as to be fully protected from any damage. My balancing spring

has a further function in that it holds the various parts of my jack assembled and positioned for operation, all as will be described.

The most important feature of my invention is, however, the simplicity of the construction of my new wheeled jack, whereby I am able to obtain easy lifting with complete safety, and whereby I am able to control the load and to lower the same without operating any system of complicated controls.

I consider my invention a distinct and valuable contribution to the prior art and do not wish to be limited in my patent monopoly to the specific structure I have shown, but rather wish to be protected in the enjoyment of my patent monopoly against the utilization of various other structures which may be devised by those skilled in the art embodying the principles of my invention.

For a description of the structure I have devised, I shall refer to the drawings wherein Fig. 1 is a view showing a skid platform elevated by my wheeled jack and ready for movement by the operator. Fig. 2 is a view of my wheeled jack separated from the skid platform and in normal resting position on the floor. Fig. 3 illustrates the wheeled jack of my invention in partial section about to be applied to the downwardly depending pin of the skid platform. Fig. 4 illustrates the parts of Fig. 3 in a slightly different position and with the weight of the skid platform about to be assumed by the wheeled jack. Fig. 5 is a view showing the parts of Fig. 4 after the front end of the skid platform has been lifted and after the handle has been elevated somewhat and into position to move the load. Fig. 6 illustrates the position of the parts when the lifting lever has been moved into a position to release the trunnion locking mechanism so as to allow the lowering of the skid platform. Fig. 7 is a view looking downwardly on my wheeled jack with the tubular lifting lever shown in section. Figs. 8, 9 and 10 are perspective views of the parts forming my invention.

Referring now more specifically to the drawings and especially to Figs. 1, 2 and 3, it will be noted that my wheeled jack or dolly cooperates with a semi-live skid platform 10 having rear wheels 11 and front supporting legs 12. In Fig. 1 the skid platform is shown supported at its forward end by the wheels of my wheeled jack, but in Fig. 3 the skid platform 10 is shown supported by its legs 12. Depending downwardly from the forward end of the skid platform is a pin 13 which is adapted to enter the socket 14 of the trunnion 15 of my wheeled jack. Through lifting of the

trunnion 15, by means to be described below, the front end of the skid platform is elevated from the position of Fig. 3 to the position of Fig. 1.

The construction of my wheeled jack is best illustrated in Figs. 3, 8, 9 and 10. There it will be noted that the wheels 16 support an axle 17 on which is mounted the main frame 18, through bearing hubs 19. The main frame of course occupies that portion of the axle which is between the two wheels 16.

Bearing hubs 20 on the main frame support trunnion shafts 21 extending at each side from the trunnion 15, as is best illustrated in Fig. 10. In this way, the trunnion 15 is allowed to hang vertically from frame 18 at all times when free. A pair of gravity dogs 22, identical in function, are also pivotally mounted on the trunnion shafts 21, their surfaces 23 cooperating with surfaces 24 formed on gravity detent plates 25 which are also freely mounted on the trunnion shafts 21. The two detent plates 25 are joined by a cross bar 26 preferably welded to the two plates. An angle iron 27 is welded to the side plates of the main frame 18 and forms a leg on which the entire dolly may rest in a manner best illustrated in Fig. 2.

In Fig. 8, I show a handle frame 28 which through bearings 29 is mounted on that portion of the main shaft 17 lying between the two side plates of the main frame 18. The handle frame 28 has fixed thereto as by welding or in any other preferred way, a tubular lifting lever 30 which has secured to its upper end a cross bar 31 forming a handle. The lifting lever 30 acts to lift the trunnion 15 and therefore the skid platform, when swung downwardly, as will be described presently.

Mounted on shaft 17 between the side plates comprising the handle carrying frame 28, is a locking lever 32 having a locking hook portion 33 and horizontally extending frame contacting surfaces 34. The end of the locking lever 32 opposite the hook portion 33 is designated by reference numeral 35, and is connected through a pin 36 with a vertical strut member 37 terminating at 38 in a piston-like portion having a lug 39. The piston-like portion 38 slides in the tubular lifting lever 30 as is illustrated. Between the lug 39 on piston 38 and an abutment 40 fixed near the upper end of lifting lever 30, there is mounted a spring 41. It is obvious that this spring tends to separate portion 35 of the locking lever 32 from the handle 30. As a matter of fact, the operation of the spring 41 will best be appreciated if it be considered that its action is the same as though a spring were inserted in the space 42 in Fig. 3 between the tubular lever 30 and handle carrying frame 28 on the one side, and the main frame 18 and arm 35 of locking lever 32 on the other side.

The surfaces 34 extending horizontally from the locking lever 32, best illustrated in Fig. 8, are forced by the spring 41 against the lower angular surfaces of the side plates of main frame 18, as is best illustrated in Fig. 3, and tend to rotate frame 18 in a counter clockwise direction about the shaft 17. At the same time, of course, the lifting lever 30 and handle carrying frame 28 are being rotated by the spring 41 in a clockwise or upward direction. It is the function of the dogs 22 previously described, to prevent the collapse of the entire apparatus and to maintain the apparatus properly assembled and positioned. For this purpose, the dogs 22 are equipped with notches 43 which in the normal position of the

parts, coat with lugs 44 of the handle carrying frame 28 to maintain the frame and handle in the position of Fig. 3, and with the space 42 between the handle carrying frame 28 and the main frame 18.

The lower end of trunnion 15 is formed with a locking nose 45 which is adapted to engage with the hook portion 33 of the locking lever 32 under conditions to be described presently. It will also be well to indicate that the gravity detent plates 25 are formed with surfaces 46 which cooperate with detent surfaces 47 of the locking lever 32, best shown in Fig. 8, all for a purpose to be described presently.

I shall now refer to the series of Figs. 2, 3, 4, 5 and 6 to describe one complete lifting and lowering operation of my wheeled jack. Referring now to Fig. 2, it will be noted that the wheeled jack is supported through its wheels 16 and leg 27 on the floor. The dogs 22 cooperate with lugs 44 on the handle carrying frame 28 to maintain the handle carrying frame and the main frame in the position of Fig. 2 and against collapse through the action of the handle balancing spring 41. The trunnion 15 hangs in a substantially vertical position, and of course the locking lever 32 is positioned with its surfaces 34 against the lower edges of the side plates of the main frame 18 by the pressure of the handle balancing spring 41.

By swinging the tubular lifting lever 30 from its position of Fig. 2 to its position of Fig. 3, the trunnion 15 may be positioned with its socket 14 directly under the pin 13 of the skid platform, as in Fig. 3. The parts of the wheeled jack remain, however, in the same relation as in Fig. 2, all through the action of the dogs 22 which maintain the handle carrying frame 28 in somewhat spaced relation to the main frame 18, the space being shown and designated by reference numeral 42 in Fig. 3.

Downward swinging of the lifting lever 30 to its position of Fig. 4 moves the trunnion 15 against the surface 43 from which depends the pin 13 of the skid platform. Once this has been done, it will readily be appreciated that the trunnion 15 will accept the load on the skid platform, and that it will thereafter be possible to rotate the handle carrying frame 28 through downward pressure on the lifting lever 30 in opposition to the pressure of the handle balancing spring 41. This brings the parts into the position of Fig. 4 and releases the handle carrying frame 28 from dogs 22 which dogs then drop by gravity until their surfaces 23 contact the surfaces 24 of the gravity detent plates 25. This is actually the position of the parts in Fig. 4. No lifting has taken place. All that has happened is the compression of handle balancing spring 41, and the releasing of the lifting lever from dogs 22.

The actual lifting of the skid platform by further downward swinging movement of the lifting lever 30 is best illustrated in Fig. 5. There it will be noted that the main frame 18 has been rotated to bring the trunnion shafts 21 and the trunnion 15 into a position corresponding to an elevation of the front end of the skid platform 10. The cam surface 45a to the rear of the locking nose 45 of the trunnion 15, has, during this movement of the main frame 18, first contacted the cam surface 49 of the locking lever 32 so as to cam the locking lever downwardly against the force of the balancing spring 41. As the hook portion 33 of the locking lever 32 then moved into a position opposite the locking nose

45 of the trunnion 15, the locking lever 32 moved under the influence of the spring 41 whereby to effect the engagement of the locking nose 45 with hook 33, as is illustrated in Fig. 5.

With the parts in this position, it is obvious that the trunnion 15 is locked by the locking lever 32 relatively to the main frame 18 and the axle 17, so that the main frame can no longer rotate relatively to the trunnion 15. Since the trunnion of course cannot rotate due to the action of pin 13, the skid platform 10 will be maintained in its elevated position supported by the wheels 16 of my wheeled jack. The lifting lever 30 and its carrying frame 28 may now be moved as to their position of Fig. 5 to transport the skid platform to any desired location, without any interference from dogs 22.

Should it now be desired to lower the load, it is of course necessary to first release the trunnion 15 from the locking lever 32 by the movement of the hook 33 of the locking lever 32 away from the nose 45 of the trunnion. This is accomplished by the operator of the wheeled jack assuming the load by proper manipulation of the lifting lever. The release of the trunnion 15 is best illustrated in Fig. 6, wherein it will be noted that the lifting lever 30 has moved the main frame 18 about the axis of the axle 17 to a position somewhat beyond the normal elevated position of Fig. 5.

Since during this movement of main frame 18 the trunnion 15 is held by the skid platform pin 13 against any rotary movement whatsoever, the following action takes place: The cam surface 50 of the locking lever 32 moves against the surface 45a of the trunnion as the locking lever 32 moves with the main frame 18 to the position of Fig. 6, and the fixed trunnion surface 45a forces the locking lever 32 out of locking relation to the trunnion and into a position wherein detent surfaces 47 of lever 32 interlock with the surfaces 46 of the gravity detent plates 25. This movement of lever 32, of course, releases main frame 18 for movement relatively to the trunnion 15. It should be noted also that the movement of the gravity plates 25 into the position of Fig. 6, that is, into cooperation with the detent surfaces 47 of lever 32, moves the dogs 22 into position for cooperation with the lugs 44 of the handle carrying frame 28, all as is quite apparent.

If now the operator allows the lifting lever 30 to move upwardly, the detent plates 25 will continue holding the locking lever 32 so that its locking hook portion 33 will move past the locking nose 45 of the trunnion without engaging it. This will allow a rotation of the main frame 18 about the axle 17 and relatively to the trunnion 15 so as to lower the trunnion and place the load of the skid platform on its legs 12. At the same time, the dogs 22 will have dropped by gravity with their surfaces 23 against surfaces 24 of the detent plates 25. This moves the notches 43 of dogs 22 into cooperation with the lugs 44 of the handle carrying frame 28, as is seen in Fig. 6, so as to control that frame.

When the skid platform has been positioned so as to be supported by its legs 12, a further rotation of the handle carrying frame 28 and the lever 30 will bring the bar 26 connecting detent plates 25 against the flat surface 26a of the trunnion 15 so that the plates 25 are incapable of further rotation with the locking lever 32. A slight further movement of the locking lever 32 with the lifting lever 30 and frame 18, releases the locking lever from the detent plates 25, restoring the

locking lever 32 to its normal functioning position of Figs. 2 and 3.

I believe that the simplicity of operation of my invention will now be apparent. It will also be apparent that many changes in actual structure may be made without departing from the basic principles of my contribution to the art.

I now claim:

1. In a combination of the class described, a frame mounted on a wheel supported shaft for rotation in the axis of said shaft, a lifting trunnion pivoted on said frame, said trunnion being adapted for engagement with means on a skid platform to be lifted and to be maintained by said means thereafter in a predetermined position, a locking lever pivoted relatively to said frame and adapted to lock said frame relatively to said trunnion when said trunnion is in an elevated position whereby to lock said frame against reverse pivotal movement to lower said trunnion, a lifting lever for rotating said frame about said axis whereby to lift said trunnion, and means actuated by rotation of said frame somewhat beyond a position corresponding to full lifting of said trunnion, for releasing said trunnion from said locking lever.
2. In a combination of the class described, a frame mounted on a wheel supported shaft for rotation in the axis of said shaft, a lifting trunnion pivoted on said frame, said trunnion being adapted for engagement with means on a skid platform to be lifted and to be maintained by said means thereafter in a predetermined position, a locking lever pivoted relatively to said frame and adapted to lock said frame relatively to said trunnion when said trunnion is in an elevated position whereby to lock said frame against reverse pivotal movement to lower said trunnion, a lifting lever for rotating said frame about and means whereby application of lifting pressure by said lifting lever to move said frame and trunnion beyond the elevated position of said trunnion releases said trunnion from said locking lever.
3. In a combination of the class described, a frame mounted on a wheel supported shaft for rotation in the axis of said shaft, a lifting trunnion pivoted on said frame, said trunnion being adapted for engagement with means on a skid platform to be lifted and to be maintained by said means thereafter in a predetermined position, a locking lever movable to lock said frame relatively to said trunnion when said trunnion is in an elevated position whereby to lock said frame against reverse pivotal movement to lower said trunnion, a lifting lever pivoted relatively to said frame and adapted to rotate said frame about said axis whereby to lift said trunnion, and a spring between said lifting lever and said locking lever tending to rotate said levers in opposite directions.
4. In a combination of the class described, a frame mounted on a wheel supported shaft for rotation in the axis of said shaft, a lifting trunnion pivoted on said frame, said trunnion being adapted for engagement with means on a skid platform to be lifted and to be maintained by said means thereafter in a predetermined position, a locking lever movable to lock said frame relatively to said trunnion when said trunnion is in an elevated position whereby to lock said frame against reverse pivotal movement to lower said trunnion, a lifting lever for rotating said frame about said axis whereby to lift said trunnion, a spring between said lifting lever and said locking lever tending to rotate said levers in opposite directions, and a dog pivoted on said frame and

cooperable normally with said lifting lever to maintain said lifting lever against said rotation.

5. In a combination of the class described, a frame mounted on a wheel supported shaft for rotation in the axis of said shaft, a lifting trunnion pivoted on said frame, said trunnion being adapted for engagement with means on a skid platform to be lifted and to be maintained by said means thereafter in a predetermined position, a locking lever movable to lock said frame relatively to said trunnion when said trunnion is in an elevated position whereby to lock said frame against reverse pivotal movement to lower said trunnion, a lifting lever for rotating said frame about said axis whereby to lift said trunnion, a spring between said lifting lever and said locking lever tending to rotate said levers in opposite directions, means on said locking lever pressing on said frame and thereby tending to impart rotation to said frame, and means between said lifting lever and said frame for limiting the relative movement between said lifting lever and said frame, whereby said spring holds said frame, locking lever and lifting lever in predetermined related positions.

6. In a combination of the class described, a frame mounted on a wheel supported shaft for rotation in the axis of said shaft, a lifting trunnion pivoted on said frame, said trunnion being adapted for engagement with means on a skid platform to be lifted and to be maintained by said means thereafter in a predetermined position, a locking lever movable to lock said frame relatively to said trunnion when said trunnion is in an elevated position whereby to lock said frame against reverse pivotal movement to lower said trunnion, a lifting lever for rotating said frame about said axis whereby to lift said trunnion, means for releasing said locking lever from said trunnion when said trunnion and frame are moved to a position slightly beyond the normal lifted position of said trunnion, and means for thereafter maintaining said locking lever in releasing position until said trunnion and frame move to a lowered position.

7. In a combination of the class described, a frame mounted on a wheel supported shaft for rotation in the axis of said shaft, a lifting trunnion pivoted on said frame, said trunnion being adapted for engagement with means on a skid platform to be lifted and to be maintained by said means thereafter in a predetermined position, a locking lever movable relatively to said frame and adapted to lock said frame relatively to said trunnion when said trunnion is in an elevated position whereby to lock said frame against pivotal movement to lower said trunnion, a lifting lever for rotating said frame about said axis whereby to lift said trunnion, and means for releasing said locking lever from said trunnion when said trunnion and frame are moved by said lifting lever to a position slightly beyond the normal lifted position of said trunnion and for thereafter maintaining said locking lever in releasing position until said trunnion and frame move to a lowered position.

8. In a combination of the class described, a frame mounted on a wheel supported shaft for rotation in the axis of said shaft, a lifting trunnion pivoted on said frame, said trunnion being adapted for engagement with means on a skid platform to be lifted and to be maintained by said means thereafter in a predetermined position, a locking lever pivoted relatively to said frame and adapted to lock said frame relatively

to said trunnion when said trunnion is in an elevated position whereby to lock said frame against pivotal movement to lower said trunnion, a lifting lever for rotating said frame about said axis whereby to lift said trunnion, means for releasing said locking lever from said trunnion when said trunnion and frame are moved to a position slightly beyond the normal lifted position of said trunnion, a detent adapted to hold said locking lever in releasing position thereafter to allow lowering movement of said frame and trunnion, and means for moving said detent out of holding position as said trunnion is lowered whereby to restore said locking lever to its normal functioning position.

9. In a combination of the class described, a frame mounted on a wheel supported shaft for rotation in the axis of said shaft, a lifting trunnion pivoted on said frame, said trunnion being adapted for engagement with means on a skid platform to be lifted and to be maintained by said means thereafter in a predetermined position, a locking lever movable to lock said frame relatively to said trunnion when said frame elevates said trunnion through rotation on its axis, a lifting lever for rotating said frame to lift said trunnion, and a surface of said trunnion cooperable with said locking lever to cam said lever out of locking position when said frame and locking lever are rotated to a position beyond the position corresponding to a normal elevation of said trunnion.

10. In a combination of the class described, a frame mounted on a wheel supported shaft for rotation in the axis of said shaft, a lifting trunnion pivoted on said frame, said trunnion being adapted for engagement with means on a skid platform to be lifted whereby to be maintained by said means thereafter in a predetermined position, a locking lever movable to lock said frame relatively to said trunnion as said frame elevates said vertically maintained trunnion through rotation on its axis, the said rotation of said frame moving said locking lever into locking relation to said trunnion, a lifting lever for rotating said frame to lift said trunnion, a surface of said trunnion cooperable with said locking lever to cam said lever out of locking position when said frame and said locking lever are rotated to a position beyond the position corresponding to a normal elevation of said trunnion, and a detent adapted to hold said locking lever in trunnion releasing position thereafter whereby to allow reverse rotation of said frame to lower said trunnion.

11. In a combination of the class described, a frame mounted on a wheel supported shaft for rotation in the axis of said shaft, a lifting trunnion pivoted on said frame, said trunnion being adapted for engagement with means on a skid platform to be lifted and to be maintained by said means thereafter in a predetermined position, a locking lever movable to lock said frame relatively to said trunnion as said frame elevates said vertically maintained trunnion through rotation on its axis, the said rotation moving said locking lever into locking relation to said trunnion, a lifting lever for rotating said frame to lift said trunnion, a surface of said trunnion cooperable with said locking lever to cam said lever out of locking position when said frame is rotated to a position beyond the position corresponding to a normal elevation of said trunnion, a detent adapted to hold said locking lever in trunnion releasing position thereafter to allow

reverse rotation of said frame to lower said trunnion, and means for camming said detent out of holding relation to said locking lever as said trunnion is lowered whereby to restore said locking lever to its normal functioning position.

12. In a combination of the class described, a frame mounted on a wheel supported shaft for rotation in the axis of said shaft, a lifting trunnion pivoted on said frame, said trunnion being adapted for engagement with means on a skid platform to be lifted and to be maintained by said means in a predetermined position, a locking lever pivoted relatively to said frame, a lifting lever for rotating said frame about its axis whereby to lift said trunnion, spring means pressing said lifting and locking levers in opposite directions, said locking lever being adapted to lock said frame to said trunnion when said frame elevates said vertically maintained trunnion through rotation on its axis, a dog pivoted on said frame and adapted to lock said lifting lever against said spring pressed movement beyond a predetermined position allowing said lifting lever a slight amount of free rotation against said spring pressure prior to actuating said frame, the rotation of said lifting lever through said distance against said spring pressure and while said trunnion and frame are held by contact with the means on the skid platform being sufficient to release the lever from said dog.

13. In a combination of the class described, a frame mounted on a wheel supported shaft for rotation in the axis of said shaft, a lifting trunnion pivoted on said frame, said trunnion being adapted for engagement with means on a skid platform to be lifted whereby to be maintained by said means in a vertical position, a locking lever pivoted relatively to said frame, a lifting lever for rotating said frame about its axis whereby to lift said trunnion, spring means pressing said lifting and locking levers in opposite directions, said locking lever being adapted to lock said frame to said trunnion when said frame elevates said vertically maintained trunnion through rotation on its axis, a dog pivoted on said frame and adapted to lock said lifting lever against said spring pressed movement beyond a predetermined position allowing said lifting lever a slight amount of free rotation against said spring pressure prior to actuating said frame, the rotation of said lifting lever through said distance against said spring pressure and while said trunnion and frame are held by contact with the means on the skid platform being sufficient to release the lever from said dog, a surface of said trunnion cooperable with said locking lever to cam said lever out of locking position when said frame and said locking lever are rotated to a position beyond the position corresponding to a normal elevation of said trunnion, a detent adapted to hold said locking lever in trunnion releasing position whereby to allow reverse rotation of said frame to lower said trunnion while also moving said dog into position for locking said lifting lever once again against spring pressed movement beyond said predetermined position, and means for moving said detent out of holding relation to said locking lever as said trunnion is lowered.

14. In a device of the class described, a pair of wheels and a shaft supported thereby, a main frame rotatable about the axis of said shaft, a lifting trunnion pivoted on said frame and adapted to be lifted and lowered as said frame rotates on said axis, a lifting lever for rotating said frame, a spring pressing said lifting lever up-

wardly and in a non-lifting direction relatively to said frame, and means between said frame and lifting lever for locking said lifting lever against said movement by said spring in a non-lifting direction while allowing rotation of said lifting lever in a downwardly or lifting direction relatively to said frame.

15. In a device of the class described, a pair of wheels and a shaft supported thereby, a frame rotatable about the axis of said shaft, a lifting trunnion pivoted on said frame and adapted to be lifted and lowered as said frame rotates on said axis, a lifting lever for rotating said frame, a spring pressing said lifting lever upwardly and in a non-lifting direction relatively to said frame, a dog carried by said main frame for locking said lifting lever against said spring pressed movement while allowing free rotation of said lifting lever in a downwardly or lifting direction relatively to said frame, and a foot on said frame for supporting it and its trunnion and said lifting lever in a resting position.

16. In a device of the class described, a pair of wheels and a shaft supported thereby, a frame rotatable about the axis of said shaft, a lifting trunnion pivoted on said frame and adapted to be lifted and lowered as said frame rotates on said axis, a lifting lever adapted to rotate said frame about said axis whereby to lift said trunnion, a balancing spring pressing said lifting lever upwardly and in a non-lifting direction relatively to said frame, and a gravity dog carried by said frame for locking said lifting lever against said spring pressed movement beyond a predetermined position relatively to said frame, while allowing free rotation of said lifting lever in a downwardly or lifting direction relatively to said frame.

17. In a combination of the class described, a frame mounted on a wheel supported shaft for rotation in the axis of said shaft, a lifting trunnion pivoted on said frame, said trunnion being adapted for engagement with means on a skid platform to be lifted and to be maintained by said means thereafter in a predetermined position, a locking lever pivoted relatively to said frame and adapted to lock said frame relatively to said trunnion when said trunnion is in an elevated position whereby to lock said frame against reverse pivotal movement to lower said trunnion, a lifting lever of tubular form for rotating said frame about said axis whereby to lift said trunnion, a spring in said tubular lifting lever, and means for securing said spring relatively to said frame for pressing said tubular handle and said frame in opposite directions.

18. In a combination of the class described, a frame mounted on a wheel supported shaft for rotation in the axis of said shaft, a lifting trunnion pivoted on said frame, said trunnion being adapted for engagement with means on a skid platform to be lifted and to be maintained by said means thereafter in a predetermined position, a locking lever pivoted relatively to said frame and adapted to lock said frame relatively to said trunnion when said trunnion is in an elevated position whereby to lock said frame against reverse pivotal movement to lower said trunnion, a lifting lever of tubular form for rotating said frame about said axis whereby to lift said trunnion, a spring in said tubular lifting lever, means whereby said spring is secured at its lower end to said locking lever, whereby said spring tends to swing said tubular handle upwardly relatively to said frame while simulta-

neously pressing said locking lever in a locking direction.

19. In a combination of the class described, a frame mounted on a wheel supported shaft for rotation in the axis of said shaft, a lifting trunnion pivoted on said frame, said trunnion being adapted for engagement with means on a skid platform to be lifted and to be maintained by said means thereafter in a predetermined position, a locking means for locking said frame relatively to said trunnion when said trunnion is in an elevated position whereby to lock said frame against reverse pivotal movement to lower said trunnion, a lifting lever for rotating said frame about said axis whereby to lift said trunnion, and means actuated by rotation of said frame somewhat beyond a position corresponding to full lifting of said trunnion for releasing said trunnion from said locking means.

20. In a combination of the class described, a frame mounted on a wheel supported shaft for rotation in the axis of said shaft, a lifting trunnion pivoted on said frame, said trunnion being adapted for engagement with means on a skid platform to be lifted and to be maintained by said means thereafter in a predetermined position, locking means for locking said frame relatively to said trunnion when said trunnion is in an elevated position whereby to lock said frame against reverse pivotal movement to lower said trunnion, a lifting lever for rotating said frame about said axis whereby to lift said trunnion, means actuated by rotation of said frame somewhat beyond a position corresponding to full lifting of said trunnion for releasing said trunnion from said locking means, and means for holding said locking means out of locking position until said trunnion is lowered.

21. In a combination of the class described, a frame mounted on a wheel supported shaft for rotation in the axis of said shaft, a lifting trunnion pivoted on said frame, said trunnion being adapted for engagement with means on a skid platform to be lifted and to be maintained by said means thereafter in a predetermined position, a locking lever pivoted relatively to said frame and adapted to lock said frame relatively to said trunnion when said trunnion is in an elevated position whereby to lock said frame against pivotal movement to lower said trunnion, a lifting lever for rotating said frame about said axis whereby to lift said trunnion, means for releasing said locking lever from said trunnion when said trunnion and frame are moved by said lifting lever to a position slightly beyond the normal lifted position of said trunnion, means for thereafter maintaining said locking lever in releasing position until said trunnion and frame

move to a lowered position, and means for moving said last means out of maintaining position when said trunnion is lowered.

22. In a device of the class described, a pair of wheels and a shaft supported thereby, a main frame rotatable about the axis of said shaft, a lifting trunnion pivoted on said frame and adapted to be lifted and lowered as said frame rotates on said axis, a lifting lever for rotating said frame, a spring pressing said lifting lever upwardly and in a non-lifting direction relatively to said frame, a dog for locking said lifting lever against rotation by said spring relatively to said frame beyond a predetermined position, said lifting lever moving against said spring pressure relatively to said frame when said frame is held against movement with said lever as when said trunnion is in engagement with a load to be lifted, said relative movement between the lifting lever and the frame releasing the lifting lever from said dog.

23. In a device of the class described, a pair of wheels and a shaft supported thereby, a main frame rotatable about the axis of said shaft, a lifting trunnion pivoted on said frame and adapted to be lifted and lowered as said frame rotates on said axis, a lifting lever for rotating said frame, a spring pressing said lifting lever upwardly and in a non-lifting direction relatively to said frame, and means between said frame and lifting lever for locking said lifting lever against said movement by said spring in a non-lifting direction while allowing rotation of said lifting lever in a downwardly or lifting direction relatively to said frame when said frame is held against movement with said lever as when said trunnion is in engagement with a load to be lifted.

24. In a device of the class described, a pair of wheels and a shaft supported thereby, a main frame rotatable about the axis of said shaft, a lifting trunnion pivoted on said frame and adapted to be lifted and lowered as said frame rotates on said axis, a lifting lever for rotating said frame, a spring pressing said lifting lever upwardly and in a non-lifting direction relatively to said frame, means between said frame and lifting lever for locking said lifting lever against said movement by said spring in a non-lifting direction while allowing rotation of said lifting lever in a downwardly or lifting direction relatively to said frame when said frame is held against movement with said lever as when said trunnion is in engagement with a load to be lifted, said relative movement between the lifting lever and said frame releasing said lifting lever from said means.

GEORGE QUAYLE.
